Inventor,
James W. Phelps.
By Edward Fay Wilson 1906

UNITED STATES PATENT OFFICE.

JAMES W. PHELPS, OF CHICAGO, ILLINOIS.

ELECTRIC FLASHING DEVICE.

Application filed May 24, 1924. Serial No. 715,553.

My invention relates to improvements in automatic electric flashers or cutouts, and has special reference to such cutouts of the general form disclosed in my earlier Patent 5 No. 1,476,022, dated December 4, 1923, wherein is disclosed a cutout device adapted to be interposed in circuit between a lamp and its socket.

A particular object of my invention is to 10 simplify the construction and reduce the manufacture cost of such devices.

I accomplish my main object by providing a porcelain insulation member so formed that it will readily receive the thermostatic 15 device and the central contacts for the socket and the plug at the opposite ends of the device.

Another feature of my invention resides 20 in the provision of an insulated head on the adjustable contact screw of the device, whereby the frequency of the breaks or flashes can be changed while the device is in circuit without danger of shock.

A further feature relates to the simplicity 25 of the device as a whole, comprising a metal tubular member providing a plug at one end and a socket at the other, the inner porcelain member which carries all of the connections and the thermostatic device and an insulating shell or cover.

For a clear understanding of my invention reference is had to the accompanying drawings forming part of this specification and in which:—

35 Figure 1, is a longitudinal central section of the device on the line 1—1 of Figures 2 and 6;

Figure 2, is a similar sectional view taken on the line 2—2 of Figure 1;

40 Figure 3, is an end view looking at the plug end of the device;

Figure 4, is a side elevation of the inner unit;

45 Figure 5, is a plan view of the inner unit at right angles to Figure 4, the metal members being shown separated from the insulation member;

Figure 6, is a cross section on the line 6—6 of Figure 1; and

50 Figure 7, is a diagrammatic view of the electric circuit.

In said drawings, 10 illustrates a metal tubular shell member formed into a screw socket shell 11 at one end and a screw plug 55 12 at the opposite end, whereby the device can be readily interposed between a lamp and its socket when it is desired to cause the lamp to flash. This shell is made of a length to accommodate the parts which are housed therein. In addition to the terminals provided at the two ends by the shell 10, I provide centrally located terminals at each end also. These central terminals together with the thermostatic circuit breaker and the necessary connections are constituted by a unit member shown separately in the drawings and designated 14. This unit member comprises a body member made of porcelain or other suitable insulation substance, preferably cast or pressed 60 into form and hardened. This member comprises a head 16 at one end formed suitable for closing the opening at the plug end 12 of the shell 10, and a head 17 at the opposite end suitably formed to close 75 the bottom of the socket 11. The heads are connected by a central longitudinally extending flat wall 18 which is thick enough to make the member substantial and thin enough to provide space at each side thereof 80 for the necessary connections and the thermostatic device.

The thermostatic device comprises a bimetallic strip 19 which extends through a slot 20 in the head 16 and projects near 85 one face of the wall 18 toward the opposite head 17. The outer end 21 of this strip is bent over adjacent to the outer end 22 of the head 16 to form the center contact for the plug end of the device. This member is 90 secured in place by a bolt 23 which passes through an opening 24 in the wall 18. The opening 24 is made in the form of a deep notch entering from one edge of the wall and permitting the assembly of the bolt 95 with the member 20 before attachment to the body member 15. The slot 20 in the head 16 opens through the edge of the head, whereby the bi-metallic strip can be formed complete, that is, the outer end bent over 100 before it is mounted on the body member 15, and by loosening the bolt 23 the thermostatic member can be readily removed, without distortion, from the body member 15. The inner end portion 25 of the bi-metallic strip stands free from the adjacent side of the central wall 18 and is wound with an insulated coil wire 26, which is adapted at times to heat the strip and distort it. While I have illustrated the coil 110 as shunt connected it is obvious that however the coil is connected the bi-metallic

strip can function to open and close a circuit in accordance with the flow of current.

Similar to the head 16, the head 17 is likewise provided with a slot 27 for receiving

- 5 a contact strip 28, the outer end 29 of which is bent over adjacent to the outer surface 30 of the head 17 to form the center terminal for the socket 11. The slot 27 likewise extends cut through the edge of the head 17, 10 so that the contact strip 28 can be formed before it is assembled with the body member 15. This connection strip is clamped in place by a bolt 31 which is received in a notch or slot 32. This slot 32 is similar 15 to the slot 24, in that it extends to the edge of the wall 18, and therefore the bolt can be assembled with the strip before the strip is put in place. In rapid manufacturing processes such separate assembly of parts is 20 of great advantage in the saving of time and labor. The inner end 33 of the strip 28 is bent back parallel with itself and spaced slightly from the body portion, and this end 33 and the body portion are provided 25 with threaded openings 34 and 35 aligned with each other to receive the threaded shank of an adjusting contact screw 36. The projection of the adjusting screw 36 through the two threaded openings tends, 30 on account of the slight springing of the free end 33 in the threading process, to bind the screw with sufficient friction to hold the screw from movement, except when it is purposely turned to alter its adjustment. 35 The wall 18 is provided with a third notch or slot 37 to permit this screw to pass freely through same, and its free end is adapted to contact at times with the free end of the thermostatic bar 29, which is in line with 40 the slot 37. The outer end of the adjusting screw 36 is provided with an insulation head 38, so that the screw can be adjusted when the current is on without danger of shock.

- 45 For connecting the coil 26 of the thermostatic device in shunt, one end of the coil is connected to the bi-metallic bar at 39 by soldering, and the other end 40 is carried around the edge of the wall 18 which is opposite the several notches and is carried 50 to the contact plate 28 to which it is clamped by the nut of the screw 31. The edge of the wall 18 is provided with a notch 41 in which the end 40 of the coil is located to retain it against contacting with the metallic shell. The metal tube 10 is cut away 55 at one place, as shown at 42, to permit a hub portion 43 on the screw head 38 to enter through the shell. The tubular casing being in the circuit is protected by an enclosing tube 44 of insulation, preferably some form of fibre, and this outer covering is provided with an opening 45 in which the part 43 of the head 38 fits freely, and thereby the screw and the outer casing are doweled together and held against relative

movement when they are assembled together.

In Figure 7, I have indicated the flow of the current through the device. The current enters at the plug end through the center contact 21, then through the bi-metallic 70 member to its free end and back through the coil 26 to the contact member 28. Then through the lamp or whatever is mounted in the socket 11 and back through the casing 10 to the plug end. 75

Normally, when the device is put in circuit and when the thermostatic element is shunt wound, as shown, the free end of the bi-metallic member stands free of the contact screw 36. Then when the current flows 80 through the coil 26 it heats the thermostatic member, causing its free end to contact the point of the screw 36 and close the main circuit, thus lighting the lamp. The closing of the main circuit stops the flow 85 through the coil 26, and the thermostatic element cools off and swings out of contact with the screw 36, thus opening the main circuit and causing the light to go out. Preferably the coil is of sufficient resistance to 90 prevent the flow of enough current to light the lamp.

It will now be clear that my improved flashing plug is very simple in construction, comprising as it does the inner part, the 95 metallic shell and the outer cover. The inner part can be all assembled, except the adjusting screw 36, and be pushed into place in the tubular casing, and when the adjusting screw is placed in position the parts are 100 interlocked and held together.

As many modifications of my invention will readily suggest themselves to one skilled in the art, I do not limit or confine my invention to the specific details of construction herein shown and described except within the scope of the appended claims. 105

I claim:

1. In a device of the kind described, a body of insulating material, an inner metallic conducting thermo-electric make and break structure adapted to be supported by the body, said metallic structure including metallic contact strips and fasteners therefor, said body having openings through same arranged to permit the free assembly of the preassembled metallic strips and their fasteners with the body member, the fasteners adapted to be tightened after the assembly. 115

2. In a device of the kind described, a tubular shell providing a socket at one end and a plug at the opposite end, an insulation body member for insertion into the tubular shell and providing a head for the plug and a bottom wall for the socket, metal parts mounted on said body member to form one side of a circuit extending from head to head of said body member, each head thereof provided with a slot for receiving a con- 125

- tact member and each slot extending out through the edge of its head, whereby the contact member can be placed in position edgewise after being formed, the body portion provided with openings for receiving fasteners for said contact members, and one of said contact members formed integrally with a thermo electric element, as and for the purpose specified.
5. In a device for interposition in an electric circuit for changing the flow of current therein, a bi-metallic thermostatic element having one end fixed and the other movable for opening and closing the circuit, said bi-metallic member having an integral extension of its body portion at its fixed end for forming one of the contacts of the device.
10. 3. In a device of the kind described, a tubular metal casing forming one side of the circuit, an insulation body member within the casing, metal conducting members mounted on said body member and forming the other side of the circuit, a thermostatic element forming part of the inner circuit, an adjustable screw for contact with the thermostatic element, an outer tubular protective casing, and said adjusting screw having a head of insulating material adapted 25 to retain the several parts in assembled relation.
4. In a device of the kind described, a tubular metal casing forming one side of the circuit, an insulation body member within the casing, metal conducting members mounted on said body member and forming the other side of the circuit, a thermostatic element forming part of the inner circuit, an adjustable screw for contact with the thermostatic element, an outer tubular protective casing, and said adjusting screw having a head of insulating material adapted 30 to retain the several parts in assembled relation.
5. In an electric device of the kind described, a body of hard insulation material for carrying various contact plates secured thereon by through fasteners, the body provided with notches for permitting said fasteners to be first assembled with their respective plates, and then placed in position on the body without disassembly.
35. 6. In a device of the kind described, a pre-formed rigid body member, the body portion having a head, a contact plate for forming a center contact on said head, the head provided with a slot extending axially through the head for receiving a metal strip for forming said contact, said slot opening through the edge of the head to permit the contact member to be moved edgewise into position after having its end bent over to form said center contact.
40. 7. In a flashing device of the kind described, an electrothermic responsive element, said element having a bendable strip
- projecting from one end thereof bent at substantially a right angle to form a contact, 55 an insulating head provided with a slot through which said strip after being bent can be assembled with the head to form one of the contacts of the device.
8. In a flashing device of the kind described, a preformed unitary body of insulation material formed to provide heads at the ends thereof, a thermo-electric responsive element, a metal strip extending from one end of the element and adapted to extend through one of the heads to form a contact at the outer surface thereof.
9. In a flashing device of the kind described, a body made of insulation material, metal parts and fasteners therefor 60 adapted to be held by the body, the body provided with pre-formed slots into which the metal parts can be moved edgewise and other slots into which the fasteners can be simultaneously moved after being 65 preassembled with the metal parts for assembling same with the body.
10. In a device of the kind described, a body of insulation material having heads at its opposite ends and provided with an open 70 space between its heads a thermo-electric responsive element within said space having a thin metallic strip extending from one end, a second thin metallic strip secured to said body, said thermo-electric responsive 75 element and said second strip having co-operating contacts, said heads provided with slots for receiving said strips edgewise, the outer ends of said strips adapted to be bent to form center contacts on the two heads.
11. In a device of the kind described, a body of insulation material having heads at its opposite ends and formed with a chambered space between its ends, a thermo-electric responsive make and break element in 80 said space, a thin metallic contact strip extending from one end of said element, a second thin metallic contact strip secured to said body, the body provided with slots at 85 its head portions for receiving said strips edgewise and said strips adapted to be bent over outside of respective heads to form center contacts for said device.
90. In testimony whereof, I have hereunto set my hand, this 7th day of May, 1924.
95. JAMES W. PHELPS.
